Primary Examiner — Mary Ann Calabrese*Assistant Examiner* — Rebecca S Rozin(74) *Attorney, Agent, or Firm* — Christine Flanagan(57) **CLAIM**

The ornamental design for a retail locator tag, as shown and described.

DESCRIPTION

FIG. 1 is perspective view of a retail display with the retail locator tag of the present invention attached thereto.

FIG. 2 is a perspective view of the retail locator tag of the present invention.

FIG. 3 is a front view of the retail locator tag of FIG. 2.

FIG. 4 is rear view of the retail locator tag of FIG. 2.

FIG. 5 is a right side view of the retail locator tag of FIG. 2.

FIG. 6 is a left side view of the retail locator tag of FIG. 2.

FIG. 7 is a top down view of the retail locator tag of FIG. 2; and,

FIG. 8 is a bottom up view of the retail locator tag of FIG. 2.

The broken lines are for the purpose of illustrating the environment of the design only and form no part of the claimed design.

1 Claim, 3 Drawing Sheets(56)
